COIL WINDING MACHINE

Robert L. Huffman, Palatine, Ill., assignor to General Telephone Laboratories, Incorporated, a corporation of Delaware

Application February 17, 1955, Serial No. 488,810

3 Claims. (Cl. 242—4)

This invention relates to coil winding machines and more particularly to improvements in machines for winding coils of wire on toroidal cores.

Toroidal coil winding as practiced today generally employs a hollow wire carrying ring or shuttle which is disposed to revolve at a constant rate about its axis and to interlink the core to be wound. A wire guide travels in a track on one side of the shuttle as the shuttle is rotated and guides the wire as it is drawn from the shuttle and coiled about the core. As the wire guide passes through and moves away from the core, a length of wire is drawn from the shuttle which length of wire forms a loop as the guide again approaches the core. Such a loop in the wire tends to decrease the tension of the wire, thereby loosening the last coil of wire placed on the core. Similarly the next coil of wire will be placed loosely on the core and suddenly be pulled taut. These conditions may cause consecutive convolutions of wire to overlap and also may cause wire breakage.

The prior art reveals several structures which attempt to prevent the harmful results of this wire loop formation, including A. J. Dowd, 2,367,489 and R. M. Conklin, 2,425,511. The above patents disclose stationary and movable pressure pads between which the wire in the loop must be drawn while advancing toward the core. These structures have reduced the difficulty to some extent, but in many applications, fail to overcome the problem sufficiently to produce the desired results. Such is the case when fine wire is being wound and also where extreme accuracy is desired in the laying of each convolution.

Difficulty is also encountered in toroidal winding machines in achieving proper alignment of each convolution with respect to the geometric center of the core being wound. The conventional wire guide is located at the side of the shuttle, thus causing the wire to be wound around the core in a plane other than those containing the axis of the core. The result is overlapping and unequal size of convolutions.

An object of this invention is the provision of means in a toroidal coil winding machine, simple in structure, yet highly efficient in overcoming the difficulties caused by the formation of a wire loop during each convolution.

Another object of this invention is the provision of means in a toroidal coil winding machine for assuring that the convolutions of wire are properly aligned on the core in planes containing the axis of the core through the geometric center thereof.

A feature of this invention is the provision of novel means for maintaining uniform tension on the wire during formation of the loop as the wire is drawn toward and about the core.

Another feature of this invention is the provision of novel guiding means to hold the wire in a plane through the geometric center of the core as each convolution is placed on the core.

In the present invention, a plurality of resilient bristles impinge upon a fixed pad and are disposed adjacent one

2

another between a point adjacent the core to be wound and a point adjacent the geometric center of the shuttle. The wire to be wound on the core slides across the face of the fixed pad on each revolution of the wire guide, being retarded in its progress by the ends of the resilient bristles, and thereby a constant tension on the wire is maintained, sufficient to control the wire in its advancement to the core and to overcome the harmful effects of the wire loop. Adjacent solid pads, in general use for this purpose, fail to produce the desired result principally because the frictional contact of the wire passing between the faces of the solid pads tends to produce a sag in that portion of the loop which is beneath the pads while applying the desired tension to the portion of wire above the pads. This is due to the wire failing to move upward in addition to the lateral movement across the pad. This sag beneath the pads loosens the previous convolution on the core and may cause skewing on the core and overlapping of adjacent convolutions. The plurality of bristles in place of a solid pad maintain tension on the entire wire loop since they allow an upward as well as backward pull thereacross, the bristles bending resiliently in any direction as required.

Also in the present invention, provision is made to assure proper alignment of each convolution of wire on the core in relation to the geometric center of the core. This is assured by employment of a wire guiding finger which extends through the core to be wound and holds the wire, as it is taken from the wire guide, beneath the inner face of the ring where it will be in line with the geometric center of the core.

Other objects and features of the present invention will become apparent to those skilled in the art from the following detailed description thereof when taken in conjunction with the accompanying drawings wherein:

Figure 1 is a fragmentary side elevation of a toroidal coil winding machine with the brush element removed to show the wire loop passing across a solid pad.

Figure 2 is a fragmentary plan view, partly in section, showing a brush pad and wire guiding finger in relation to a wire loop being pulled into place.

Referring now to the drawings, there is shown a conventional winding and shuttle ring 1 constructed so as to removably interlink a toroidal core 2 and interengage drive wheels 3, connected to a suitable driving means (not shown), which wheels are effective to cause the ring 1 to revolve through the core 2. The core 2 is supported by jaws 4 of the conventional type which are disposed to rotate the core about its geometric center, thereby distributing the convolutions of wire 5 uniformly on the core. A conventional wire guide 6 slidably interengages a track formed on the side of the ring 1 so that it will travel with the ring 1 yet slide on the track under the control of the wire. Lengths of wire are removed from the ring 1 at the leading end 7 of the wire guide 6 and wound about the core as the ring and wire guide revolve therethrough. The general construction of the machine is similar to that shown in the Dowd and Conklin patents mentioned earlier.

A wire guiding finger 8 is clamped to a pivoted arm 9 and secured thereon by bolt 10. The finger 8 is formed so as to pass through the core 2 adjacent and following the contour of the inner face of the ring 1 and substantially in alignment with the center line thereof. One end of arm 9 encircles and yieldably engages shaft 20, allowing the arm to swing outward for ease of insertion or removal of the core to be wound. Similarly the jaws 4 may be lowered to allow the guiding finger to be swung outward when changing cores and making other adjustments. The end of locking pin 11 fits into a recess in arm 9 and holds arm 9 in place when the guiding finger 8 is in proper position for winding.

A stationary plate or pad 12 is mounted on the frame

(not shown) in substantially the position shown in the drawings. A brush 13 is affixed to a tension spring arm 14 which in turn is fixedly held in block 18 by screws 19. Sufficient tension is applied by spring 14 to hold the bristles 15 of the brush 13 against the front face 16 of the stationary pad 12. The tension applied may be varied by loosening lock screw 17 and revolving the block 18 about the shaft 20, which passes therethrough, and again tightening lockscrew 17.

As the winding ring 1 revolves during operation of the machine, the wire guide 6, following the counterclockwise path of the ring, guides the wire 5 as it is drawn from the ring. In traveling away from the core 2, a length of wire will be pulled out through guide 6, which length of wire forms a loop as the guide again returns toward the core. This loop starts to pass across the face of the stationary pad 12 where it encounters the ends of bristles 15. The bristles maintain a constant tension on the upper and lower portions of the loop as the portion engaged by stationary pad and bristles forces its way therebetween. The lower portion is gradually pulled up and across the pad and bristles as the guide 6 advances toward and through the core 2, and the loop is almost completely wrapped about the core before the wire finally clears the brush bristles and pad releasing the tension on the wire. By this time the guide has passed completely through the core and again applies the necessary tension to the wire.

As the wire guide 6 passes through the core 2, the wire 5 engages the guiding finger 8 which pushes the wire inwardly behind the inner face of the winding ring 1, keeping it in a plane through the center line of the ring where it will be aligned with a radius of the core and form its coils in a plane containing the axis through the geometric center of the core.

Thus by employment of resilient bristles which consecutively retard the progress of the wire loop as it is pulled toward the core, a uniform tension on the wire is maintained and a firm, even convolution of wire is laid on the core. Also proper alignment on the core of each convolution of wire is assured by employment of the guiding finger which continues to guide the wire into position until the wire is completely wrapped about the core.

Although specific improvements of the invention have been shown and described, it is understood, of course, that various modifications may be made therein without departing from the scope of this invention as defined by the appended claims.

What is claimed is:

1. In a toroidal coil winding machine having a wire carrying shuttle ring disposed to interlink and revolve through a toroidal core to wind a loop of wire around said core, a stationary member within the inner periphery of said ring extending inwardly from a position adjacent said core, a brush having a plurality of resilient bristles mounted therein, said bristles having the ends thereof impinging upon the face of said stationary member, ten-

sioning means engaging the back of said brush so as to apply a desired pressure thereto, means for causing movement of the loop of wire between said stationary member and said bristles during a portion of the movement of the ring as the wire is moved toward said core, a guiding finger extending through said core in a position adjacent the rear face of said ring, said finger engaging said wire as it is pulled through the core and guiding the wire into position on said core.

2. In a toroidal coil winding machine having a shuttle ring disposed to interlink and revolve in a path substantially through the center of a toroidal core, said ring carrying a supply of wire to be wound on said core, a stationary member having one side thereof adjacent the center of said ring and the opposite side thereof adjacent said core, a tensioned base having a plurality of resilient bristles affixed thereto at their roots and having the ends thereof independently contacting a face of said stationary member, each of said bristles, during a portion of the movement of the ring, in cooperation with said stationary member offering resilient opposition to the passage of said wire therebetween, to maintain a uniform tension on said wire as it is pulled toward and around said core, a wire guiding finger projecting through said core adjacent to and following the contour of the inner face of said ring so as to guide each convolution of wire to a position on said core in a plane containing the axis through the geometric center of said core.

3. In a toroidal coil winding machine having a shuttle ring disposed to interlink and revolve in a path substantially through the center of a toroidal core, said ring carrying a supply of wire to be wound on said core, a stationary member having one side thereof adjacent the center of said ring and the opposite side thereof adjacent said core, a plurality of resilient bristles having the ends thereof independently contacting a face of said stationary member, means to vary the pressure with which said bristles contact said stationary member, each of said bristles in cooperation with said stationary member offering resilient opposition to the passage of said wire therebetween to maintain a uniform tension on said wire during a portion of the movement of the ring as it is pulled toward and around said core, a wire guiding finger projecting through said core adjacent to and following the contour of the inner face of said ring so as to guide each convolution of wire to a position on said core in a plane containing the axis through the geometric center of said core.
